UNITED STATES PATENT OFFICE.

WILLIAM F. MALLOY, OF ALLEGHENY, ASSIGNOR TO THE PITTSBURGH BRASS COMPANY, OF PITTSBURG, PENNSYLVANIA.

DESIGN FOR A LAVATORY-SUPPORT.

SPECIFICATION forming part of Design No. 22,465, dated May 23, 1893.

Application filed January 24, 1893. Serial No. 459,630. Term of patent 7 years.

To all whom it may concern:

Be it known that I, WILLIAM F. MALLOY, a resident of Allegheny, in the county of Allegheny and State of Pennsylvania, have invented a new and original Design for Lavatory-Supports; and I do hereby declare the following to be a full, clear, and exact description thereof.

My design relates to lavatory supports, and it consists in a lavatory support composed of a front and side portion each formed of a square open frame and a series of vertical ornamental spindles extending across the open space of the frame.

In the accompanying drawing the design is illustrated by a perspective view, the lavatory resting on the support being shown in dotted lines.

The lavatory support is composed of the front frame *a* and side frames *b*, said frames being open square frames formed of the top bars *c*, bottom bars *d* and end bars *e*, the bars having flat faces as shown. Extending between the top bars *c* and bottom bars *d* across the open space of the frames are the series of vertical ornamental spindles *f* which give to

the support a fret-work appearance. The ornamentation shown on the spindles consists of a series of rings at about the center thereof. The legs connected to the lavatory support but which form no part of the design are secured at the corners where the two frames *a* *b* meet, being joined to the frame-work below the same, and each having a backwardly curved upper portion *g* and the vertical body 35 portion *h*.

By the design I obtain a peculiar open work effect for the support which exposes to view the outer surface of the base which can be ornamentally finished either in shape or decoration, and at the same time a deep support which would naturally cover the basin, and which is rich in appearance.

What I claim is—

The design for a lavatory support herein shown and described.

In testimony whereof I, the said WILLIAM F. MALLOY, have hereunto set my hand.

WILLIAM F. MALLOY.
